UNITED STATES PATENT OFFICE.

LEON CHEVALLE, OF SARDIS, BRITISH COLUMBIA, CANADA.

STERILIZING APPARATUS.

1,222,932.

Specification of Letters Patent. Patented Apr. 17, 1917.

Application filed January 15, 1917. Serial No. 142,753.

To all whom it may concern:

Be it known that I, LEON CHEVALLE, citizen of the United States, residing at Sardis, in the Province of British Columbia, Dominion of Canada, have invented a certain new and useful Improvement in Sterilizing Apparatus, of which the following is a specification.

My invention relates to improvements in sterilizing apparatus, and the object of my invention is to provide a sterilizing apparatus which shall embody a container within which may be disposed fresh milk, and which apparatus shall be adapted to operate to sterilize such milk and to maintain all of it, or such portions of it as may not be withdrawn from said container, in an untainted sterilized condition, whereby such milk shall be preserved fresh and sweet.

I accomplish these objects by devices illustrated in the accompanying drawings wherein—

Figure 1 is a plan view of one form of apparatus embodying my invention;

Fig. 2 is a view of the same in side elevation with a part broken away the better to disclose internal parts;

Fig. 3 is a view of the same in vertical section on broken line 3, 3 of Fig. 1;

Fig. 4 is a fragmentary view of the same in vertical section on broken line 4, 4 of Fig. 1; and

Fig. 5 is a view in vertical section on broken line 5, 5 of Fig. 2 showing some details of the same.

Referring to the drawings, throughout which like reference numerals indicate like parts, 6 designates a supporting table upon which is disposed a container 7 of cylindrical form whose vertical cylindrical wall extends downwardly lower than its bottom wall 8 to rest its bottom edges on the top of the table 6, as shown in Figs. 2 and 3.

The container 7 is provided with a removable cover 9 that is adapted tightly to close the top end thereof.

The central portion of the bottom wall 8 of the container is provided with an outlet passageway 10 that is controlled by a faucet 11 whose outlet end is provided with a removable cap 12 which serves to protect the inner surface of said outlet end from dust when the container is not in use.

As shown only in Fig. 2, the rotatable cock 13 of the faucet 11 is connected with one bifurcated end of a spindle 14 which ex-

tends horizontally to and through a bearing 15 formed in the lower portion of the vertical cylindrical wall of the container 7 to extend therethrough, within which bearing 15 is rotatably disposed the other bifurcated end of said spindle 14, rotative movements of which spindle 14 may serve to open and close the outlet passageway of the faucet 11 through which liquid contents of the container 7 may be withdrawn as required.

A tank 16 adapted to contain air under pressure is disposed adjacent to the container 7 with the lower edge of its vertical cylindrical wall resting on the table 6.

Like the container 7, the tank 16 is provided with a bottom wall, as bottom wall 17, which is disposed at a considerable distance higher than the bottom edge of its vertical cylindrical wall, as shown more clearly in Fig. 3, and the central portion of the bottom wall 17 is provided with a passageway therethrough which is controlled by a valve 18 that is actuated by a valve-cock 19, through which passageway air under pressure may be admitted into the interior of the tank 16.

At a point lower than the bottom wall 17 the vertical cylindrical wall of the tank 16, is provided with a circular hole 20 through which one's hand may be extended to actuate the valve-cock 19 and to connect and disconnect a union 21 to the outer end of the valve 18.

The top wall of the tank 16 is provided with a needle valve case 22, whose needle-like valve member 23 is articulated with one end of a lever 24 which is pivotally mounted in a bracket 25 and whose other end is articulated to the top end of a vertically disposed connecting rod 26 which extends downwardly to a point where its lower end is articulated with a hand lever 27.

The hand lever 27 is fastened to shaft 28 which is mounted to be rotatively movable in bearings provided in a bifurcated bracket 29 that is rigidly fastened to the exterior surface of the bottom end portion of the vertical cylindrical wall of the tank 16, as shown more clearly in Figs. 2 and 4.

The shaft 28 on its end adjacent to the container 7 is flattened and its flattened portion is freely projected within the slot of the bifurcated end portion of the spindle 14, as shown more clearly in Fig. 2.

The faucet cock 13, the spindle 14 and the shaft 28 are so relatively disposed that when the hand lever 27 is in its uppermost posi-

tion, as shown in Fig. 4 (in which position it is normally maintained by a helical spring 30) then the needle valve 23 is tightly closed and the passageway through the faucet 12, which is controlled by the faucet cock 13, is also tightly closed; but when the hand lever 27 is swingingly moved downwardly to its lowest position then in the course of such movement, the needle-valve member 23 will first be raised to open the passageway through the valve-case 22, and afterward (as the hand lever 27 passes the horizontal plane indicated by broken lines 31 in Fig. 5) the passageway through the faucet 12 will open and will be wholly opened when said hand lever 27 reaches its lowermost position indicated by dotted lines 32 in said Fig. 5.

Also when the hand lever 27 is returning to its uppermost position, in response to the force of the helical spring 30, the passageway through the faucet 12 will be wholly closed before the passageway through the valve case 22 can be closed by the needle-valve member 23.

The upper portion of the vertical cylindrical wall of the container 7 is provided with an inlet passageway 33 through a valve 34 that is controlled by a cock 35, of well known form.

The outer end of the valve 34 is releasably connected by a union 36 to one end of a conduit pipe 37, whose other end is connected to the outlet passageway of the valve-case 22, as shown more clearly in Figs. 2 and 3, thus, when the valve 34 is opened by turning the cock 35, thence compressed air may flow from the interior of the tank 16 into the upper portion of the interior of the container 7 in response to a raising of the needle-valve member 23 from its seat in the valve-case 22, which needle-valve member 23 will be raised in response to a downward movement of the hand lever 27 as hereinbefore explained.

Disposed beneath the table 6 to be supported in a horizontal position, by means not shown, is a long steam heater preferably made of a length of steam pipe 38, of comparatively large diameter, both of whose opposite ends are closed to be steam tight by caps 39 and 40.

Extending through the cylindrical wall of the pipe 38, adjacent to the cap 40, is a steam pipe 41 that may be extended to a steam boiler, not shown, through which steam pipe 41 steam may be admitted to the interior of the larger steam pipe 38.

Extending through the wall of the pipe 38 adjacent to the cap 39 is a valve-controlled outlet passageway 42 through which steam or water may be permitted to escape from the interior of the pipe 38.

Disposed within the pipe 38 is a great length of smaller pipe 43 which I have

shown as being disposed in the form of a helix, one of whose end portions projects outwardly through the cap 39 and the other of whose end portions projects outwardly through the cap 40, as shown more clearly in Fig. 3, which latter end portion is extended to a source of highly compressed air, not shown.

That end of the pipe 43 which extends through the cap 39 is connected to one end of a T fitting 44, whose opposite end is connected with a pipe 45 that extends to and connects with the union 21 on the lower end of the valve 18, and to the side outlet of the T fitting 44 is connected a pipe 46 that is extended to and connects with a thermometer 47 which may indicate a temperature of the compressed air within the pipe 43.

The pipes 45 and 46, the T fitting 44 and the outwardly projecting end of the pipe 43 are provided with a lagging 48, of non-heat-conducting material, in a manner well known, and preferably the steam heater (comprising the large pipe 38 and caps 39 and 40) is also lagged with non-heat-conducting material.

To utilize the apparatus thus illustrated and described, the faucet 11 and the valve 34 being closed the cover 9 is removed and such quantity of fresh milk is disposed within the container 7 as will cause its surface to be lower than the passageway 33, whereupon said cover is replaced tightly to seal said container 7, and thereupon said container 7 is heated to such temperature as will sterilize the milk and air therein contained, such process of heating being accomplished by any convenient well known means, not shown, as, for instance, by the flames of gas burners.

The valve 18 being closed steam is admitted into the large pipe 38 through the pipe 41 under such pressure as will adequately heat the steam pipe 43 therewithin, the passageway 42 being opened sufficiently to give circulation to said steam, then air under high pressure is admitted into the pipe 43 from a source of highly compressed air and after such compressed air within the pipe 43 is sufficiently heated thoroughly to sterilize it then the valve 18 is opened to admit such hot compressed air into the tank 16 to sterilize the air already contained therein.

Thus the tank 16 will be filled with highly compressed, sterilized air and the container 7 will contain sterilized milk and the air above its surface and within the pipe 37 will have been sterilized by other heating means, as described.

Under such conditions no unsterilized air can gain access to the interior of the container 7 during the operation of withdrawing milk from the container 7 in response to

manipulations of the hand lever 27, by which manipulations air is always admitted into the container 7 through the valve-case 22 and pipe 37 before the faucet 12 is opened 5 and the faucet 12 is always closed before the passageway through the valve-case 22 is closed.

Obviously, many changes may be made in the forms, dimensions and arrangement of 10 parts of my invention without departing from the spirit thereof.

What I claim is:

1. In a sterilizing apparatus of the class described, the combination with a container 15 provided with an outlet faucet in its lower portion and an inlet passageway in its upper portion, of a tank containing compressed sterilized air; a valve-controlled pipe connecting the interior of said tank 20 with said inlet passageway; and mechanism operatively disposed to connect the valve-cock of the valve of said valve-controlled pipe with the valve-cock of said faucet and adapted to be manually operated first to 25 admit said sterilized air into said container and thereafter to open the passageway through said faucet.

2. In a sterilizing apparatus of the class described, the combination with a container 30 provided with an outlet faucet in its lower portion and an inlet passageway in its upper portion, of a tank containing compressed sterilized air; a valve-controlled pipe connecting the interior of said tank with said 35 inlet passageway; mechanism operatively disposed to connect the valve-cock of the valve of said valve-controlled pipe with the valve-cock of said faucet and adapted to be manually operated first to admit said 40 sterilized air into said container and thereafter to open the passageway through said faucet; a valve-controlled pipe one terminal of which connects with the interior of said

tank; a source of compressed air connected to the other terminal of said pipe; and heating means associated with said pipe whereby the compressed air within said pipe may be heated to sterilize it during its passage from said source of compressed air into said tank. 45 50

3. In a sterilizing apparatus of the class described, the combination with a container provided with an outlet faucet in its lower portion and an inlet passageway in its upper portion, of a tank containing compressed sterilized air; a valve-controlled pipe 55 connecting the interior of said tank with said inlet passageway; mechanism operatively disposed to connect the valve-cock of the valve of said valve-controlled pipe 60 with the valve-cock of said faucet and adapted to be manually operated first to admit said sterilized air into said container and thereafter to open the passageway through said faucet; a valve-controlled pipe 65 having one of its terminals connected with the interior of said tank; a source of compressed air to which the other terminal of said valve-controlled pipe is connected; a receptacle for steam through which said 70 valve-controlled pipe extends in an irregular course to subject it to the heat of steam that may be contained in said receptacle whereby compressed air may be sterilized during its passage through said valve-controlled pipe and means for maintaining steam under pressure within said receptacle. 75

In witness whereof I hereunto subscribe my name this 5th day of January, A. D. 1917. 80

LEON CHEVALLE.
